TRAIN DISPATCHING SYSTEM FOR RAILROADS

Filed Nov. 25, 1929

UNITED STATES PATENT OFFICE

SEDWICK N. WIGHT, OF ROCHESTER, NEW YORK, ASSIGNOR TO GENERAL RAILWAY SIGNAL COMPANY, OF ROCHESTER, NEW YORK

TRAIN DISPATCHING SYSTEM FOR RAILROADS

Application filed November 25, 1929. Serial No. 409,605.

This invention relates to train dispatching systems, and more particularly to systems of the type in which the movement of trains is dispatched through the medium of way-

5 side signal indications. the apparatus at the distant interlocking plant, whereas the apparatus in the dispatcher's office is confined within the dotted rectangle DO.

5 In my prior application, Ser. No. 120,423 filed July 3, 1926, there has been disclosed a train dispatching system in which the dispatcher may directly control the wayside 10 signals and other traffic controlling devices at a distant point, to advise and aid the engineer in the movement of his train over the tracks. In some cases it is experienced that there is an interlocking plant at a distant 15 point on the railway system, where an operator is present at all times, such interlocking plant in many cases being one of the manually operated type, as distinguished from a power interlocking plant, and in accordance 20 with the present invention it is proposed to handle such manually operable interlocking plant through the medium of a dispatching system of the type disclosed in my prior application.

25 More specifically, it is proposed to provide the operator in said distant interlocking plant with a miniature track layout corresponding to the interlocking plant over which he has control, to associate indicators 30 with said miniature track layout which signals are capable of informing the operator what routes to set up, and to control these miniature signals from the distant office. A further object of the present invention re- 35 sides in the provision of means whereby the passage of a train over certain track circuits is directly and automatically indicated in the dispatcher's office through the medium of the same line circuits through which the dispatcher informs the operator as to what 40 routes to set up.

45 Other objects, purposes and characteristic features of this invention will in part be obvious from the accompanying drawings and will in part be pointed out in the detail description hereinafter.

50 In describing the invention in detail reference will be made to the accompanying drawings, in which the portion at the right-hand side thereof illustrates conventionally

55 Referring to the right-hand portion of the drawings, although the invention may be applied to single track railway signalled with absolute-permissive-block signaling, it has for convenience been shown applied to a double track railway system, which is crossed 60 by a single track railway having signals 1 and 2 associated therewith. The north track of the double track railway system is illustrated by rails 3, divided by insulating joints 4 into track sections, of which one section 65 is provided with a track battery 5 and a track relay TN. This same track section is also provided with derails DNW and DNE, these derails being controlled through the medium of a lever L⁵ and suitable intercon- 70 necting mechanism conventionally represented by the dotted line 10. Similarly the south track of the double track railway system is represented by rails 7, divided by insulating joints 8 into track sections of which one track section is track-circuited by the track relay TS and a track battery 9. This latter section is provided with derails DSW and DSE, which are controlled by the lever L⁶ and through the medium of suitable 75 mechanism designated by the dotted line 6. 80

Further, these two tracks are connected by a crossover CO¹, which is controlled by the lever L⁷ through the medium of mech- 85 anism 14. Also, these tracks are connected by a crossover CO² controlled by the lever L⁸ and mechanism 15.

At the approach to the crossover CO¹ there is provided a main signal SS and a take-siding signal DS, which signals are controlled through the medium of circuits conventionally shown at 16 and 18 and are interlocked so that only one of these signals can be cleared depending on the position of the switch points of the crossover; whereas the crossover CO² has associated therewith a main signal SN and a take-siding signal DN similarly interlocked, these signals being controlled through the medium of cir- 90 95 100

More specifically, the signals SN, DN, SS and DS are controlled through the medium of circuits conventionally illustrated by dotted lines 19, 17, 16 and 18, so organized that 5 a particular signal can only clear if the corresponding control repeater relays 20, 21, 22 or 23 is energized, the associated crossover assumes the proper position, and traffic conditions in advance are clear, all as shown in 10 my prior application Ser. No. 120,423 above referred to. Also, if desired both of the railway tracks shown may be signaled for both directions of train movement, as by absolute-permissive-block signaling, if desired. 15

Adjacent the levers L^3 , L^4 , L^5 and L^6 there is provided a miniature track layout containing the signals N, S, E and W, which signals inform the interlocking tower operator whether a train is to pass over the lower 20 track or the upper track and whether it is to take one or the other of the two crossovers shown, all as more clearly pointed out hereinafter. In the interlocking tower are also provided control relays ZW and ZE, which 25 are controlled from the dispatcher's office DO, the control relay ZW in turn controlling repeater relays 20 and 21, whereas the control relay ZE controls repeater relays 22 and 23. There are also provided slow-acting bell 30 relays BW and BE, which are used in connection with the sounding of the alarm or bell BL, as pointed out in the operation of the system hereinafter.

In the dispatcher's office DO there is provided a miniature track layout for two 35 crossovers associated therewith, one of which is provided with a miniature signal w and the other of which is provided with a miniature signal e . Similarly, the upper track is provided with a track circuit occupancy indicating lamp ITN and the lower track is provided with an indicator ITS. There are provided two levers LW and LE 40 in the dispatcher's office which levers respectively control the control relays ZW and ZE, there being included in the energizing circuit for the relay ZW the indicating relay WR, and there being included in the energizing circuit of the control relay ZE, an indicating relay ER. Having 45 now briefly pointed out all of the various elements of the system, many of which have been conventionally represented, it is deemed expedient to point out the cooperation 50 of these elements in the operation of the system.

Operation:—Let us first assume that the dispatcher wishes to allow a train moving from left to right over the railway track 55 7 to cross the track of the other railway system. In order to do so, he will operate the lever LW to the right, thereby completing the following circuit for the control relay ZW:—beginning at the positive terminal of the battery 25, wires 26 and 27, lever

LW, wires 28 and 29, winding of the indicating relay WR, line wire 30, contact of the track relay TS, wire 31, winding of the relay ZW, wires 32 and 33, to common return wire C connected to the midpoint of 70 said battery.

Completion of the circuit just traced causes the relays WR and ZW to assume their energized position, the control relay ZW being energized toward the right by 75 reason of the direction of the flow of the direct current. With the control relay ZW energized toward the right the relay 21 will be energized through a circuit containing the neutral contact 40 and polar contact 41 80 to the right of the relay ZW. With the relay 21 energized the indicator S is rendered active, thus informing the interlocking operator that he is to set up traffic to permit passage of the train in question. 85

In order for the dispatcher to clear the signal SS, the operator in the interlocking tower must first place the derails DSW and DSE in their inactive position, and this is accomplished by movement of the lever L^4 90 which can only be moved if the signals 1 and 2 of the conflicting route are at stop. After these derails have been moved to their inactive position signal SS may clear in response to the energized condition of relay 95 21, thus permitting the train in question to proceed, assuming of course that traffic conditions in advance are clear.

As the train in question accepts the signal SS and enters and treads upon the track 100 circuit containing track relay TS, the control relay ZW is deenergized, and this approach of the train is indicated to the operator by the inaction of his indicator S. In this connection, it should be noted that the operator's attention is directed to the lighting of the lamp S by the sounding of the bell BL, this bell being sounded through the following circuit:—beginning at the battery terminal B, front contact 65 of the relay 21, 105 wires 66, 67 and 68, back contact 69 of the relay BW, wires 70 and 71, winding of the bell BL, to the other terminal C of said battery. After a short time the relay BW will 110 pick up, it also deriving its energy through the contact 65, after which the bell circuit will be opened at the contact 69 of relay BW, so that the bell BL is sounded momentarily only. Similarly, dropping of the 115 track relay TS opens the energizing circuit for the indicating relay WR in the dispatcher's office DO, thereby causing this relay WR to assume its retracted position, effecting illumination of the track occupancy 120 indicating lamp ITS, so that the dispatcher is informed of the passage of the train by the point in question, and he will return his lever to the neutral position which in turn 125 will advise the operator in the interlocking 130

plant to retain the signal SS at stop upon passage of the train in question.

Let us now assume that another train is approaching, moving from left to right over the same track 7, and that the dispatcher wishes this train to proceed over the crossover CO¹ to cross the conflicting route through the medium of the track 3. In order to give this information the dispatcher

- 10 will move his lever LW toward the left. Movement of lever LW to the left effects energization of the relays WR and ZW, but under this condition the control relay ZW will be energized toward the left, thereby
- 15 effecting energization of the relay 20, which relay 20 in turn will assume its attracted position and through the medium of contact 43 illuminate the indicator W. Also, with the lever LW toward the left the indicators
- 20 w in the dispatcher's office will be rendered active through the following circuit:— beginning at the negative terminal of the battery 25, wire 44, lever LW, wires 28 and 35, front contact 36 of the relay WR, wire 37,
- 25 lever contact 38, wire 45, indicating lamp w, to common return wire C.

- The indicator W associated with the lever in the interlocking tower thus informs the operator that he must set up a route over the crossover CO¹ and he will do this by operating the lever L³ and L⁵. The approach of the train on the track 7 from left to right upon accepting the signal DS will pass over the crossover CO¹ and over the derails DNW and DNE. The operator will now move his lever LE toward the left and will thereby energize the control relay ZE and the indicating relay ER through the following circuit:—beginning at the negative terminal battery 25, wires 44, 46 and 47, lever LE, wires 48 and 49, relay ER, wire 50, front contact of track relay TN, wire 51, winding of the relay ZE, wires 33 and C, back to the mid-point of the battery 25.
- 40 The completion of these circuits picks up the relay ER and prevents energization of the indicating lamp ITN in the dispatcher's office DO. Also, with the relay ZE now energized toward the left the repeater relay 22 is energized, resulting in the energization of the indicating lamp N. This indicating lamp N when energizing in combination with the indicating lamp W informs the operator that an east bound train movement is
- 45 to take place over the route identified by these lamps W and N. The signal SN will, however, not be cleared even though the relay 22 is energized, this by reason of the fact that the crossover CO¹ is in its reverse position and local interlocking prevents the clearing of the signal SN.
- 50 As this train treads upon the track circuit containing the track relay TN, the control relay ZE and the indicating relay ER
- 55 will be de-energized, thereby effecting ex-

tinguishment of the indicating lamp N due to dropping of the relay 22, and also effecting illumination of the indicating lamp ITN in the dispatcher's office through the following circuit:—beginning at the negative terminal of the battery 25, wires 44, 46, and 47, lever LE, wires 48 and 56, back contact 57 of the relay ER, wire 62, indicating lamp ITN, to the common return wire C connected to the midpoint of battery 25.

Let us now assume that there is a train moving from east to west on the track 3, and that the dispatcher wishes this train to continue its movement on track 3 and pass over the conflicting route as soon as possible. To accomplish this, the dispatcher will move his lever LE toward the left thereby closing the following energizing circuit for the control relay ZE and the indicating relay ER connected in series therewith:— beginning at the negative terminal of the battery 25, wires 44, 46 and 47, lever contact LE, wires 48 and 49, winding of the indicating relay ER, line wire 50, front contact on the track relay TN, wire 51, winding of the control relay ZE, wires 33 and C, back to the midpoint of the battery 25. Completion of this circuit causes the relays ER and ZE to assume their energized position, the relay ZE being energized toward the left by reason of the direction of current flow in the circuit just traced.

With the control relay ZE energized toward the left the repeater relay 22 is energized through a circuit including the contacts 52 and 53 of the control relay ZE, thereby completing a circuit for the indicating lamp N, including the front contact 54 of the relay 22, readily traced in the drawings. Energization of the relay 22 will, of course, momentarily sound the bell BL for reasons heretofore given. The operator in the interlocking tower in response to the illumination of the indicating lamp N, this informing him that a train is to pass over the track 3 without taking any one of the cross overs, will operate the lever L⁵ to close the derails DNW and DNE. If now the derails DNW and DNE have been closed, the cross overs CO¹ and CO² are both closed, traffic conditions in advance of this signal SN are clear and the repeater relay 22 energized as just explained, the upper arm signal SN will assume the clear position through the circuit conventionally illustrated by the dotted line 19, so that the train in question may proceed over the track 3, this of course on the assumption that there is no train moving on the conflicting route. If there were a train moving on the conflicting route, or the signals 1 or 2 on this conflicting route were clear, the dispatcher would have been unable to close his derails DNW and DNE.

Passage of the train in question over the

track circuit including the track relay TN and battery 5 will effect opening of the energizing circuit for the control relay ZE and the indicating relay ER, the interlocking operator will be informed of this train movement by the extinguishment of the indicator N, and the dispatcher will be informed of this fact by the illumination of the indicating lamp ITN. After the train in question has passed and the dispatcher has been informed of this fact, he will return the lever NE to its neutral position, thereby informing the interlocking operator through the extinguishment of the indicating lamp N, that he may again open the derails DNW and DNE, this indicating lamp N in the meantime having been illuminated in response to movement of the train off of the track circuit containing the track relay TN. Obviously, a train may be directed over the crossover CO², in exactly the same manner as already explained in connection with the crossover CO¹, and for this reason it is deemed unnecessary to explain this operation specifically. It may however be pointed out that in this case the dispatcher will move his lever LE toward the right, and illuminate the indicating lamp E through contacts 57 and 59 and wire 58, and similarly cause illumination of the indicator E through the medium of front contact 72 of the relay 23.

A system has been devised in which the dispatcher may inform an operator at a distant interlocking plant as to how he shall control the movement of trains through his interlocking plant through the medium of signal indications displayed before the operator, and further means has been provided to give an OS indication in the dispatcher's office in response to train movements through said interlocking plant, this latter OS indication being given over the same line wires which are used for informing the interlocking tower operator as to what route he shall set up for the train in question.

Having thus shown and described one specific embodiment of the present invention, it is desired to be understood that the particular arrangement illustrated has been selected for the purpose of facilitating description of the invention, and has not been selected for the purpose of showing the scope of the invention or the exact construction preferably employed in practicing the same, and that various changes, modifications, and additions may be made to adapt the invention to the particular interlocking plant to which the invention is to be applied, all without departing from the spirit or scope of the invention or the idea of means underlying the same, except as demanded by the scope of the following claims.

What I claim is:—

1. The method of dispatching the move-

ment of trains, which consists in visually indicating to the operator at a distant interlocking plant from an invisible point the routes to be set up in said plant, and in having an operator in such plant act on such visual indication and set up such routes. 70

2. The method of dispatching the movement of trains, which consists in visually indicating at a distant interlocking plant the routes to be set up in such plant, in having an operator in such plant act on such visual indications and set up such routes, and in advising the dispatcher of the passage of trains over such routes. 75

3. The method of dispatching the movement of trains, which consists in visually indicating the routes to be set up in a distant interlocking plant, in informing the operator of such plant audibly of a change in such visual indications, and in having said operator in such plant act on such visual indications and set up such routes. 80

4. The method of dispatching the movement of trains, which consists in visually indicating the routes to be set up in a distant interlocking plant, in informing the operator of such plant audibly of a change in such visual indications, and in having said operator in such plant act on such visual indications and set up such routes, and in advising the dispatcher of the passage of trains over such routes and by such signals. 95

5. In a train dispatching system, the combination with a dispatcher's office, a distant interlocking plant and an associated interlocking tower; of levers in said interlocking tower for operating the traffic controlling devices of said interlocking plant; visual indicators in said tower for informing the operator as to what route he shall set up; and means for controlling said visual indicators from said dispatcher's office. 100

6. In a train dispatching system, the combination with a dispatcher's office, a distant interlocking plant and an associated interlocking tower; of levers in said interlocking tower for operating the traffic controlling devices of said interlocking plant; visual indicators in said tower for informing the operator in such tower as to what route he shall set up; means for controlling said visual indicators from said dispatcher's office; and means for indicating in the dispatcher's office the passage of a train over said route. 110

7. In a train dispatching system, the combination with a dispatcher's office, a distant interlocking plant and an associated interlocking tower; of levers in said interlocking tower for operating the traffic controlling devices of said plant; visual indicators in said tower for informing the operator of said interlocking plant as to what route he shall set up, means for audibly informing said operator of a change in said indicators; 120

and means for controlling said visual indicators from said dispatcher's office.

8. In a train dispatching system, the combination with a dispatcher's office, a distant 5 interlocking plant and an associated interlocking tower; of levers in said interlocking tower for operating the traffic controlling devices of said interlocking plant; visual indicators in said tower for informing the 10 operator thereat as to what route he shall set up; means for audibly informing said operator of a change in said indicators; means for controlling said visual indicators from said dispatcher's office, and means for 15 indicating in the dispatcher's office the passage of a train over said route.

9. In a train dispatching system, the combination with a dispatcher's office, a distant 20 interlocking plant and an associated interlocking tower; of levers in said interlocking tower for operating the traffic controlling devices of said interlocking plant; visual indicators in said tower for informing the operator thereat as to what route he 25 shall set up; means for audibly informing said operator of a change in said indicators; means for controlling said visual indicators from said dispatcher's office over a single 30 line circuit, and means for indicating through the medium of said same line circuit and in the dispatcher's office the passage of a train over said route.

10. In a train dispatching system, the combination with a dispatcher's office, a distant 35 interlocking plant and an associated interlocking tower; of levers in said interlocking tower for operating the traffic controlling devices of said interlocking plant; wayside signals in said interlocking plant; 40 visual indicators in said tower for informing the operator in such tower as what route he shall set up; means for controlling said visual indicators and said wayside signals from said dispatcher's office; and means for 45 indicating in the dispatcher's office the passage of a train over said route.

11. In a train dispatching system, the combination with a dispatcher's office, a distant 50 interlocking plant including an associated interlocking tower; of levers in said interlocking tower for operating the traffic controlling devices of said interlocking plant; visual indicators in said tower for informing the operator as to what route he 55 shall set up; wayside signals associated with said traffic controlling devices; means for controlling said visual indicators and said wayside signals from said dispatcher's office over a single line circuit, and means for indicating through the medium of said same line circuit and in the dispatcher's office the 60 passage of a train over said route.

12. The method of dispatching the movement of trains, which consists in visually 65 indicating at a distant interlocking plant

the route to be set up in such plant as determined by the dispatcher, in having an operator in such plant act on such visual indications and set up such route, and in having the dispatcher clear signals over said route when said route has been otherwise set up.

13. The method of dispatching the movement of trains, which consists in visually indicating at a distant interlocking plant the route to be set up in such plant as determined by the dispatcher, in having the dispatcher clear signals over said route when said route has been otherwise set up, and in informing the dispatcher of the passage of trains over such routes.

14. In a train dispatching system, the combination with a dispatcher's office, a distant interlocking plant including an associated interlocking tower, of levers in said interlocking tower for operating the traffic controlling devices of said interlocking plant, visual indicators in said tower for informing the operator as to what route he shall set up, wayside signals associated with said traffic controlling devices, means for controlling said visual indicators and said wayside signals from said dispatcher's office over a single line circuit, which signals can only clear if the proper route has been otherwise set up, an indicating relay in said dispatcher's office included in series in said circuit, a track circuit controlled contact at said interlocking plant included in series in said circuit, whereby the opening of said contact due to the passage of a train will inform the dispatcher thereof by deenergization of said indicating relay.

15. In a train dispatching system, the combination with a dispatcher's office, a distant interlocking plant including an interlocking tower, of levers in said interlocking tower for operating the track switches of said interlocking plant, visual indicators in said tower for informing the operator as to what route he shall set up by operating some of said switches, means for controlling said visual indicators from said dispatcher's office over a single line circuit, and means for indicating through the medium of said line circuit and in the dispatcher's office the passage of a train over said route.

16. In a train dispatching system, the combination with a dispatcher's office, a distant interlocking plant including an interlocking tower, of levers in said interlocking tower for operating the track switches of said interlocking plant, visual indicators in said tower for informing the operator as to what route he shall set up by operating some of said switches, means for controlling said visual indicators from said dispatcher's office over a single line circuit, signals for governing the movement of trains through said plant, means for controlling said signals from said dispatcher's office subject to

the proper positions of track switches, and means for indicating through the medium of the same line circuit and in the dispatcher's office the passage of a train over such route.

- 5 17. In a train dispatching system, the combination with a dispatcher's office, a distant interlocking plant including an associated interlocking tower, of levers in said interlocking tower for operating derails in said interlocking plant, visual indicators in said tower for informing the operator as to what derail he shall operate, means for controlling said visual indicators from said dispatcher's office over a single line circuit, and means for indicating through the medium of said line circuit and in the dispatcher's office the passage of a train over such derail.
- 10 18. In a train dispatching system, the combination with a dispatcher's office, a distant interlocking plant including an associated interlocking tower, of levers in said interlocking tower for operating derails in said interlocking plant, visual indicators in said tower for informing the operator as to what derail he shall operate, means for controlling said visual indicators from said dispatcher's office over a single line circuit, signals for governing the movement of trains
- 15 over such derail, means for clearing such signals from said dispatcher's office providing the associated derails are in the proper position, and means for indicating through the medium of said same line circuit and in the dispatcher's office the passage of a train over such derail.
